Attorney

UNITED STATES PATENT OFFICE

THOMAS W. MITCHELL, OF INDIANAPOLIS, INDIANA

BATH ATTACHMENT

Application filed July 29, 1929. Serial No. 381,701.

This invention relates to bath attachments and one feature of the invention is the provision of a seat that may be attached to or made a part of any preferred form of bath tub.

5 A further feature of the invention is the provision of a shield or hood for the seat portion of the attachment.

A further feature of the invention is the 10 provision of means for discharging streams of water over the body of the bather while in a sitting posture and at the same time prevent the water being splashed over the floor surface.

15 Other objects and advantages will be hereinafter more fully set forth and pointed out in the accompanying specification.

In the accompanying drawing which is made a part of this application,

20 Figure 1 is a perspective view of a bath tub with the attachments applied thereon.

Figure 2 is a longitudinal sectional view through the bath tub and attachments, and

25 Figure 3 is a front elevation of the seat and the shield therefor removed from the tub.

Referring to the drawings, the numeral 1 indicates a bath tub, which may be of the usual or any preferred make, and 2 indicates a seat structure, which is preferably provided 30 with a vertical wall 3, along the side edges and rear portion thereof, the rear portion of said wall being preferably curved to fit the contour of the body of the bather.

The top edge of the wall 3 is preferably 35 provided with an outwardly extending flange 4, which fits over the top edges of the bath tub 1 for supporting the seat a prescribed distance from the bottom of the tub.

Extending upwardly from the seat structure 40 2 and preferably resting on the flange 4, is a shield or hood 5, said shield being formed in one piece or built up of any suitable material, such as tile blocks or the like and extends a sufficient height above the seat structure to protect the body of the bather and prevent water from splashing onto the floor of the bath room.

Any suitable means may be employed for 45 discharging water over the body of the bath- er, such as a pipe member 6, which is prefer-

ably located within the shield 5 and at a height to spray water over the body of the bather below the head, or any number of the spray pipes may be provided, as may be desired and said pipes may be located at any 55 suitable height within the shield.

The upper face of the flange 4 is preferably provided with an upwardly extending rib 7, which forms a brace for the lower edge of the shield and prevents leakage of water at this 60 point, said rib being especially required when the shield is built up of blocks of tiling or the like.

While I have illustrated in a general way, certain instrumentalities which may be employed in carrying my invention into effect, it is evident that many modifications may be made in the various details, without departing from the scope of the appended claims, it being understood that my invention is not 70 restricted to the particular examples herein described.

What I claim is:

1. In a bath attachment, a seat structure adapted to be entered in a bath tub, a flange 75 on said seat structure adapted to support the seat structure within the bath tub, and a shield extending upwardly from said seat structure.

2. In a bath attachment, a seat adapted to 80 be positioned within a bath tub, a flange on said seat for supporting the same, a shield associated with said seat, and a rib extending upwardly from the flange of said seat adapted to form a brace for said shield and prevent leakage at the point of connection between said seat and shield.

In testimony whereof, I have hereunto set my hand on this the 24th day of July, 1929.

THOMAS W. MITCHELL. 90
